UNITED STATES PATENT OFFICE.

BÉLA GÁTI, OF BUDAPEST, HUNGARY.

METAL-PROTECTED HIGH-POTENTIAL INSULATOR.

1,277,304.

Specification of Letters Patent. Patented Aug. 27, 1918.

Application filed July 22, 1915. Serial No. 41,392.

To all whom it may concern:

Be it known that I, BÉLA GÁTI, a subject of the King of Hungary, residing in Budapest, Hungary, consulting technician, have 5 invented certain new and useful Improvements in Metal-Protected High-Potential Insulators, of which the following is a specification.

The subject matter of the present invention relates to a modification of the well-known metal case insulators for high potential currents in which the metal casing covering the insulation body projects beyond the insulation body and the surface of the 10 same not covered by the metal casing is formed in accordance with the principles of electrostatic strain.

In Figure 1 of the accompanying drawing there is illustrated one of these well-known insulators in vertical section, while Fig. 2 represents other embodiments of the 15 subject matter of the invention.

In all the figures the metal casing projecting over the insulating material 2 is designated by 1, the connecting grooves by 3 and the support by 4.

The insulating material 2 can consist of porcelain, glass, or any other desired suitable insulating material, but especially of 20 rubber or hard rubber, and the free surface of the same between the casing and the support is developed according to the principles of electrostatic strain. The generatrix of 25 said surface is shaped in such a way that it is perpendicular to the successive longitudinal sections of the insulator body between the metal casing and support. Said longitudinal sections are cone shaped surfaces situated within each other whose generatrices in their ensemble represent a beam 30 of rays between the metal and support. In the practical form, however, not only the edges, but a portion of the outer and inner halves of the free surfaces of the insulator 35 body may be constructed as a cone-shaped surface perpendicular to the metal casing or support, and the middle portion only may be a convex surface without any great deviation of the free insulating surface from the 40 electrostatic principle being caused thereby. The theoretical or the above mentioned practical form of the free surface of the insulator body corresponding to the electrostatic principle has, however, the disadvantage 45 that it does not afford sufficient protection against the unfavorable influence of mois- 50

ture upon the insulation capacity, since, because the surface deviates only slightly from the horizontal, the drops of water deposited upon the same cling to it. 60

For avoiding this disadvantage, in accordance with the present invention, the inner and outer halves of the free surface of the insulating body, while preserving as far as possible the form corresponding to the electrostatic principle, are displaced from each other in a vertical direction and connected with each other by a vertical or almost vertical surface. 65

The free surface of the insulating body 70 represents, therefore, no longer a surface deviating only a little from the horizontal, but a form after the manner of a reverse curved surface, the approximately horizontal portions of which are shaped in accordance with 75 the principle of electrostatic strain while the portion near the point of inflection forms a surface affording an effective protection against the unfavorable influence of the moisture and of the deposited dirt. As regards the approximately vertical part a deviation is made, it is true, from the electrostatic principle, but on the one hand concentration of the electric potential is produced thereby only on a small, intermediate 80 point which lies in a zone in which the distance between the metal casing and the support is much greater than in the upper portion of the insulating body, and the fall of potential is unimportant; and on the other 85 hand, the disadvantage caused by this slight deviation from the principle of electrostatic strain is advantageously balanced on account of the better protection against the moisture 90 of the air. 95

In accordance with Fig. 1 the middle connecting surface is shaped concave, whereby there is produced an almost vertical diverting surface for the deposited moisture, while in accordance with Fig. 2 the halves of the 100 free surface perpendicular to the metal casing and the support are connected with each other by a vertical surface 5, which also, is advantageous to avoid difficulty with the soot and dirt layers which endanger the insulating capacity. 105

I claim as my invention:

1. An improved insulator for high frequency or high potential currents, comprising an insulating body and a metal casing 110 covering a portion of the said insulating body, the exposed portions of the surface of

the said body having the form of a curved surface, whose outwardly extending portions are formed in accordance with the electrostatic strains, while the portions lying in the region of the inflection are disposed substantially vertical.

2. An improved insulator for high frequency or high potential currents, comprising an insulating body and a metal casing covering a portion of the said insulating body, the exposed portions of the surface of the said body having the form of a reverse

curved surface, whose outwardly extending portions are formed in accordance with the electrostatic strains, while the portions lying in the region of the inflection are disposed substantially vertical. 15

In witness whereof, I have hereunto signed my name in the presence of two subscribing witnesses.

BÉLA GÁTI.

Witnesses:

SIGMUND JERNAUER,
HUGH KEMENY.
